UNITED STATES PATENT OFFICE

LEE W. MELCHER, OF WINNETKA, ILLINOIS

AIR CONDITIONING SYSTEM FOR RAILWAY CARS

Original application filed September 2, 1930, Serial No. 479,227. Divided and this application filed July 9, 1931. Serial No. 549,623.

The invention relates generally to air conditioning systems. More particularly the invention relates to that type of system which is designed primarily for use in connection with a railway car and operates to cool, as well as filter or clean, the air within the car.

One object of the invention is to provide a system of this type which comprises an air conditioning unit consisting of an air filter on the bottom of the car-body and a motor-driven fan for forcing air through the filter and delivering the filtered air under pressure into the car.

Another object of the invention is to provide a system of the last mentioned character in which the motor-driven fan of the air conditioning unit is connected so as to discharge the filtered air upwardly around and longitudinally of one of the sets of pipes which are located at the sides of the car, and serve, when steam is passed therethrough, to heat the car.

Another object of the invention is to provide an air conditioning system of the character and type under consideration in which the air filter is disposed in a housing having a valve-controlled inlet for air outside the car and a valve-controlled inlet for air in the car so that the motor-driven fan may be used to deliver air from the outside or from the inside of the car.

A further object of the invention is to provide a system of the aforesaid character which includes in addition to the air conditioning unit, an independent motor-driven refrigerating unit whereby the filtered air may be cooled prior to delivery into the car.

A still further object of the invention is to provide a system for conditioning air within a railway car which includes a plurality of air conditioning units and refrigerating units and embodies devices whereby the various units may be separately or individually controlled.

In addition, the invention contemplates as one of its objects, providing an air conditioning system for a railway car which is generally of new and improved construction, may be manufactured at a low and reasonable cost and is extremely efficient in operation by virtue of the fact that it contemplates the delivery of warm or cool fresh air into the car.

Other objects of the invention and the various advantages and characteristics of the present air conditioning system will be apparent from a consideration of the following detailed description.

The invention consists in the several novel features which are hereinafter set forth and are more particularly defined by claims at the conclusion hereof.

In the drawings which accompany and form a part of this specification or disclosure and in which like numerals of reference denote corresponding parts throughout the several views:

Fig. 1 is a diagrammatic plan view of a railway car that is equipped with an air conditioning system embodying the invention;

Fig. 2 is a vertical transverse section of the car;

Fig. 3 is a view, partly in section and partly in elevation, of one of the air conditioning units and the refrigerating unit that is associated therewith;

Fig. 4 is a side view of the air conditioning and refrigerating units of Fig. 3; and

Fig. 5 is a section on the line 5-5 of Fig. 4.

The system which forms the subject matter of the present invention is designed to condition the air in a railway car 6 and comprises a plurality of air conditioning units 7, 8, 9, 10, 11 and 12. The railway car 6, as illustrated in the drawings, embodies a floor 13 and a pair of sides 14 and 15. The sides are hollow and support a roof 16. A series of pipes 17 is located adjacent

the lower portion of each of the sides of the car. These pipes extend lengthwise of the car and are adapted during cold weather, to have steam or any other suitable heating fluid circulated therethrough in order to heat the car.

The air conditioning unit 7 is in the form of an attachment and comprises an air filter 18 and a fan 19. It is located under the 10 floor 13 of the car and is suspended from a plate 20. The latter is secured beneath the floor in any suitable manner. The fan 19 operates to draw air through the filter 18 and to deliver the filtered air into the car. It 15 comprises a casing 21 and a fan-wheel 22. The fan-casing is formed of cast metal and is provided at the upper end thereof with an outlet 23 and a flange 24. The flange 24 is secured against the under face of the plate 20 by means of bolts 25 and forms with the bolts a connection whereby the fan is detachably suspended from the bottom of the railway car. The fan-wheel 22 is disposed in the casing and is driven by means of an 25 electric motor 26. The latter is secured by bolts 27 to the inner side of the fan-casing 21 and is provided with an armature shaft 28 which extends into the fan-casing and supports the fan-wheel 22. The outer 30 side of the fan-casing is provided with an eye 29. During operation of the electric motor 26, the fan-wheel 22 is driven and operates to draw air through the eye 29 and to discharge the air upwardly through the 35 outlet 23.

A flanged ring 30 is bolted to the top face of the plate 20 and communicates with the outlet 23 by way of an opening 20^a in the plate. A sheet metal duct 31 is secured to the upper end of the ring and extends through the floor 13 of the car. The duct is arranged so as to deliver the filtered air from the fan to the space around the series of pipes 17 which are associated with the 40 side 14. A sheet metal shield 32 is located over the upper end of the duct 31. It extends longitudinally of and over the portions of the pipes adjacent the duct and has open ends for the discharge of the filtered 45 air into the car. A deflector 33 is mounted in the upper end of the duct 31 and is arranged so that the filtered air is divided and directed longitudinally of the pipes in opposite directions. When steam is applied 50 to the pipes 17 at the side 14 of the railway car, the filtered air which is forced upwardly through the flanged ring 30 and the duct 31 is confined to movement longitudinally of the car by the shield 32 and is heated by the portions of the pipes within 55 the shield prior to discharge through the ends of the shield and into the car. By connecting the outlet of the fan so that it discharges around the pipe 17, it is not necessary to use a separate or special heating de-

vice for the filtered air during cold weather. In addition, an efficient circulation of heated air takes place within the car during operation of the fan and supply of steam to the pipes 17. By utilizing the sheet metal shield 70 32, the filtered air is caused before discharge into the interior of the car, to travel longitudinally of the pipes and thus become heated.

The filter 18 through which air is drawn by the fan 19 for cleaning or purification purposes, is disposed in a sheet metal housing 34. This housing is positioned outwardly of the fan-casing 21 and is provided at the inner side thereof with a flange 35. The 75 latter fits around a flange 36 which is formed integrally with the fan-casing and defines the eye 29. The filter is of the self-contained type and comprises a rectangular frame 37, a mass of filter material 38 and sheets 39 and 40 of wire screen. The frame fits removably in the outer side portion of the housing 34 and serves to hold the sheets 39 and 40 in spaced relation. The filter material 38 is formed of hair, wire or any other 80 suitable substance and is confined between the sheets 39 and 40. Prior to placement in the housing 34, the filter is dipped in light oil so as to form on the filter material 38 and the sheets 39 and 40 a film or coating to 85 which all dust particles and impurities adhere during passage of air through the filter. In order to clean the filter, it is only necessary to remove the frame 37 from the sheet metal housing 34 and dip it in a solution of 90 soda or any other cleaning fluid so as to remove the dust particles from the filter material 38. After cleaning, the filter is dipped in light oil and is replaced in the housing. Upon replacement of the filter in the housing 100 and operation of the motor 26 for the fan, air is drawn into the housing, passes through the filter by which it is cleaned and is then forced upwardly under pressure 105 through the outlet 23, the flanged ring 30 and the duct 31.

A hood 41 is removably secured to the outer side of the sheet metal housing 34. This hood embodies an inlet 41^a and supports a series of shutters 42. The latter are 110 supported pivotally by the housing so that they may be opened or closed to control the ingress of air from the outside of the car through the inlet 41^a. Any suitable mechanism may be employed to control the shutters, such, for example, as an arm which extends upwardly between the walls of the sides 14 and is arranged so that it may be 115 operated from the interior of the car. In cold weather, it is sometimes desirable to 120 cut off some or all of the air from outside of the car and to draw air from the car. In view of this fact a pipe 43 is connected to the top of the hood 41. This pipe extends 125 upwardly through an opening in the plate 130

20 and projects into the space between the inner and outer walls of the side 14. The pipe 43 receives air from the car through an inlet 44 in the inner side wall of the side 14. This inlet is located adjacent the roof of the car, as illustrated in Fig. 2 of the drawings, and is controlled by a series of shutters 45. Any suitable controlling mechanism may be provided for the shutters 45. By regulating the shutters 42 and 45, the air entering the housing 34 may be controlled so that all or a portion of the air is taken from the outside or from the inside of the car. During warm or hot weather, 15 the shutters 45 may be closed and all of the air drawn into the housing 34 through the inlet 41. In cold weather, the shutters 42 may be closed and all of the air drawn into the housing by way of the inlet 44. The 20 shutters 42 and 45 operate as valves for the inlets 41 and 44, and in conjunction with said inlets, form simple means whereby the fan may be made to act upon or to draw air through the filter from either the outside or 25 the inside of the car.

The air conditioning unit 7 is associated with a refrigerating unit 46 for cooling the air in warm weather when no steam is applied to the pipes 17. This unit is supported removably from the fan-casing 21 and comprises a compressor 47. The latter is of usual construction and is contained in a casing 48 which is provided at the upper end thereof with a flange 49. This flange 30 is secured by bolts 50 to a flange 51 on the bottom of the fan-casing 21 and forms with the bolts a connection whereby the refrigerating unit is supported removably from the fan-casing. A gear-case 52 is associated 35 with the compressor casing 48. The compressor is driven by an electric motor 53. This motor embodies a housing which is provided with a flange 54. The latter is secured by bolts 55 to the gear-case 52. The compressor 40 is driven by the motor through the medium of a sprocket 56 which is fixed on the armature shaft 57 of the motor and drives a chain 58. The chain drives a sprocket 59 which is fixed to the crank shaft 55 45 of the compressor. The sprockets 56 and 59 and the chain 58 are contained in the gear-case 52 and are accessible for repair or replacement purposes through an opening which is normally closed by a removable 50 plate 61. A pipe 62 is provided with a suitable control valve 63 and receives refrigerant from the high-pressure side of the compressor 47. This pipe conducts the refrigerant to a condenser coil 64 which is contained in an open housing or frame 65 on the bottom portion of the compressor casing 48. A pipe 66 delivers the cooled refrigerant to an expansion-valve 67. An expansion coil 55 of the radiator type comprises upper and lower heads 68 and connecting pipes 69 and

is disposed in the filter-housing 34 between the filter and the eye 29 of the fan so that the air, after passing through the filter, will be cooled in transit to the fan while the refrigerating unit is in operation. The upper 70 head 68 is connected to the expansion valve 67. The expansion coil is supported on an extension of the flange 49 of the compressor-casing so that it forms a part of the refrigerating unit and extends upwardly 75 through an opening 70 in the bottom of the housing into the space between the filter and fan. It is removable from the housing 34 when the unit is disconnected or detached from the fan-casing 21. 79 which are suitably mounted within the car and serve to permit of independent or separate control of the refrigerating units. The branch conductors 75 are connected to 5 the motors for the refrigerating units and serve to connect the latter to the line conductors 74 so as to complete the circuit for the motors for the refrigerating units. By utilizing a plurality of separately or individually controlled air conditioning units in combination with a plurality of separately or individually controlled refrigerating units, the air in different zones or portions of the car may be conditioned. It is therefore possible in the event that one portion of the car requires more cooling or heating than other portions, to operate the unit for that portion of the air within the car.

The operation of the system is as follows: 20 When the air within the car 6 is too warm for the comfort of the passengers, the conductor or any other attendant of the car will close the switches 77 and 79 so as to cause both the air conditioning and refrigerating units to operate to cool and filter the air within the car. When the temperature of the air within the car is such that cooling is unnecessary, the switches 79 are opened so as to render inoperative the refrigerating 25 units. When the switches 79 are opened, the fans of the air conditioning units serve to draw air through the filters and to discharge the air under pressure into the car in a cleaned or purified condition. In cold 30 weather when steam is supplied to the pipes 17 along the sides 14 and 15 of the car, the refrigerating units may be left inoperative or may be removed. By controlling the shutters 42 and 45, fresh air may be delivered into the car or the air in the car may be 35 re-circulated.

The herein described air conditioning system is exceedingly efficient in operation and serves to furnish to zones or localized 40 portions within the car, cleaned warm or cool air. By virtue of the fact that the various units of the system are in the nature of attachments and are removable, repair work may be readily carried out. An advantage 45 and a characteristic of the present system resides in the fact that it may be applied without change or substantial reconstruction of the railway car to which it is applied.

The invention is not to be understood as 50 restricted to the details set forth, since these may be modified within the scope of the appended claims, without departing from the spirit and scope of the invention.

This application for Letters Patent is a 55 division of my application which matured into Letters Patent No. 1,825,808 dated October 6, 1931.

Having thus described the invention, what I claim as new and desire to secure by 60 Letters Patent, is:

1. The combination with an inclosure having heating pipes therein, of an air filter supported exteriorly of the inclosure, a conduit extending through one of the walls of the inclosure and leading to the pipes, a motor-driven fan also supported exteriorly of the inclosure and connected to force air through the filter and to discharge the filtered air under pressure through the conduit and then around the pipes and into the inclosure, and a separately controllable refrigerating unit associated with the filter and fan and comprising a refrigerant line positioned to cool the air forced through the filter by the fan and adapted to be used 70 when the pipes are not employed for heating purposes.

2. The combination with an inclosure of a housing supported exteriorly of the inclosure and embodying a valve-controlled 85 inlet for air from the inclosure and a valve-controlled inlet for air outside of the inclosure, an air filter mounted in the housing, a conduit extending through one of the walls of the inclosure, a motor-driven fan also supported exteriorly of the inclosure and connected to draw air into the housing via either or both of the inlets and then through the filter and to discharge the filtered air under pressure 90 through the conduit into the inclosure, and a refrigerating unit associated with the housing and fan and comprising a refrigerant line positioned to cool the air prior to discharge by the fan into the inclosure.

3. The combination with an inclosure, of a housing supported exteriorly of the inclosure and embodying a valve-controlled inlet for air from the inclosure and a valve-controlled inlet for air outside of the inclosure, an air filter mounted in the housing, a conduit extending through one of the walls of the inclosure, a motor-driven fan also supported exteriorly of the inclosure and connected to draw air into the housing via either or both of the inlets and then through the filter and to discharge the filtered air under pressure through the conduit into the inclosure, and a refrigerating unit associated with the 105 housing and fan and comprising a refrigerant line extending through an opening into the housing and positioned between the filter and the fan to cool the filtered air prior to discharge by the fan through the 110 conduit.

4. The combination with an inclosure having heating pipes therein, of a housing supported exteriorly of the inclosure and embodying a valve-controlled inlet for air from the inclosure and a valve-controlled inlet for air outside of the inclosure, an air filter mounted in the housing, a conduit extending through one of the walls of the inclosure and leading to 125

the pipes, a motor-driven fan also supported exteriorly of the inclosure and connected to draw air into the housing via either or both of the inlets and then through 6 the filter and to discharge the filtered air through the conduit and then around the pipes and into the inclosure, and a separately controllable refrigerating unit associated with the housing and fan and comprising a 10 refrigerant line positioned within the housing to cool the air forced through the filter by the fan and adapted to be used when the pipes are not employed for heating purposes.

15 5. The combination with a railway car, of an air filter mounted under the body of the car, a conduit extending through the bottom of the car, a motor-driven fan also mounted under the car-body and connected to draw air through the filter and to discharge the filtered air through the conduit into the car, and a refrigerating unit associated with the filter and fan and comprising a refrigerant line positioned to cool the air 20 forced through the filter by the fan.

25 6. The combination with a railway car, of a housing mounted under the body of the car and having a valve-controlled inlet for air from the interior of the car and a valve-controlled inlet for air from outside of the car, an air filter disposed in the housing, a conduit extending through the bottom of the car, and a motor-driven fan also mounted under the car-body and connected to draw 30 air into the housing via either or both of the inlets and then through the filter and to force the filtered air under pressure through the conduit into the car.

35 7. The combination with a railway car, of a housing mounted under the body of the car and having a valve-controlled inlet for air from the interior of the car and a valve-controlled inlet for air from outside of the car, an air filter disposed in the housing, a conduit extending through the bottom of the car, a motor-driven fan also mounted under the car-body and connected to draw air into the housing via either or both of the inlets and then through the filter and to force the 40 filtered air under pressure through the conduit into the car, and a refrigerating unit associated with the housing and fan and comprising a refrigerant line positioned to cool the air as it is discharged by the fan 45 into the car.

50 8. The combination with a railway car, of a housing mounted under the body of the car and having a valve-controlled inlet for air from the interior of the car and a valve-controlled inlet for air from outside of the car, an air filter disposed in the housing, a conduit extending through the bottom of the car, a motor-driven fan also mounted under the car-body and connected to draw air into 55 the housing via either or both of the inlets

and then through the filter and to force the filtered air under pressure through the conduit into the car, and a refrigerating unit associated with the housing and fan and comprising a refrigerant line extending into 70 the housing and between the filter and fan and operative to cool the filtered air prior to discharge by the fan into the car.

9. The combination with a railway car having a series of longitudinally extending steam pipes along the inner face of one side thereof for heating purposes, of a housing mounted under the body of the car and having a valve-controlled inlet for air from the interior of the car and a valve-controlled inlet for air from outside of the car, an air filter disposed in the housing, a conduit extending through the bottom of the car and leading to the pipes, a motor-driven fan also mounted under the car-body and connected to draw air into the housing via either or both of the inlets and then through the filter and to force the filtered air through the conduit and then around the pipes and into the car, and a separately controllable 80 refrigerating unit mounted under the car-body and comprising a refrigerating coil positioned to cool the air drawn through the filter by the fan and adapted to be used when the pipes in the car are not employed 85 for heating purposes.

10. In a system of the character described, the combination with a railway car, of a plurality of independent air conditioning units mounted under the car-body and connected to supply cleaned air into different portions of the car via ducts extending through the car-bottom, each of said units comprising an air filter, a fan for forcing the air through the filter and into the car, 100 and a motor for driving the fan, and means for separately controlling the fan motors of the units from the interior of the car.

11. In a system of the character described, the combination with an inclosure, of a plurality of air conditioning units connected to supply cleaned air to different portions of the inclosure, each of said units comprising an air filter, a fan for forcing the air through the filter and into the inclosure, and 110 a motor for driving the fan, a plurality of motor-driven refrigerating units associated with the air conditioning units respectively and embodying refrigerant lines for cooling the filtered air, and means for individually 115 controlling the motors of the air conditioning and refrigerating units.

12. In an air conditioning system of the character described, the combination with a railway car, of a plurality of independent air conditioning units mounted under the car-body and connected to supply cleaned filtered air into different portions of the car, each of said units comprising an air filter, a fan for forcing air through the filter 125 130

and into the car, and a motor for driving the fan, a plurality of motor-driven refrigerating units associated with the air conditioning units respectively and embodying refrigerant lines positioned to cool the air cleaned by the filters, and means for separately controlling the motors for the air conditioning and refrigerating units.
